J. H. DOÉRRES.

COAL BREAKER OR CRUSHER

Filed May 8, 1924

Fig. 1.

Inventor:
J. H. Doerres,
By *Wm. W. Cope*
Attorney.

UNITED STATES PATENT OFFICE.

JOHN H. DOERRES, OF ST. LOUIS, MISSOURI, ASSIGNOR TO PENNSYLVANIA CRUSHER COMPANY, OF NEW YORK, N. Y., A CORPORATION OF NEW YORK.

COAL BREAKER OR CRUSHER.

Application filed May 8, 1924. Serial No. 711,778.

To all whom it may concern:

Be it known that I, JOHN H. DOERRES, a citizen of the United States, and a resident of the city of St. Louis, Missouri, have invented certain new and useful Improvements in Coal Breakers or Crushers, of which the following is a specification.

My invention relates to certain improvements in that type of structure known as 10 a Bradford breaker, comprising a cylindrical cage or screen made up of longitudinal members supported by end rings attached to central hubs by suitable spokes, and screen plates which are secured to said 15 longitudinal members. These structures are of very large size and the amount of material passing through the same is such that the screen plates under normal screening conditions are subjected to tremendous 20 strains and stresses due to the weight of the falling material undergoing crushing and screening.

One object of my invention is to provide 25 an improved form of screen plate having an increased area of contact with the supporting means therefor, and a further object of my invention is to provide improved means for securing the screen plates to their supporting members.

30 These and other features of my invention are more fully described hereinafter; reference being had to the accompanying drawings, in which:

Figure 1, is a cross sectional view of a 35 Bradford breaker or crusher, showing the use of my improved screen plates and the manner of mounting them with respect to their supporting members in accordance with my invention.

40 Fig. 2, is a perspective view of one of my improved screen plates.

Fig. 3, is a fragmentary sectional view on a larger scale illustrating in greater detail the manner in which my improved plates 45 are secured to the longitudinal supporting members of the breaker or crusher structure, and

50 Figs. 4 and 5, are sectional views illustrating modified details of construction within the scope of my invention.

My present improvements relate to the character of the screen plates; the manner of mounting them with respect to the longitudinal supporting members, and the manner 55 of securing the same thereto.

In the former practice the foraminous plates employed in making up the screen drum, usually perforated plates, have been mounted on the longitudinal supporting members with their meeting edges abutting 60 in lines substantially parallel with the longitudinal axis of the screen drum. The longitudinal supporting members were usually I-shape in cross section, and the plates were secured in place by bolts or rivets passing 65 through apertures adjacent to the edges of the same and through apertures in the flanges of said longitudinal members. Additionally, the abutting plates heretofore employed were curved on the arc of a circle 70 struck from the axis of rotation of the screen element which they form.

In carrying out my invention the longitudinal members, which may be of I-shape or other suitable cross section, are provided 75 with a supporting portion or flange normal to the axis of rotation, that is to say, at right angles to radial lines passing through the axis of rotation; each longitudinal supporting member presenting a support with 80 an engaging surface in such relation. It will be understood, of course, that with respect to each other, such surfaces are not in line but are spaced apart and approximate a cylindrical wall to which the several 85 screen plates are secured.

The screen plates forming the subject of my invention and which I propose to employ to make up the screen drum are rectangular and flat. They may be of any 90 suitable length longitudinally of the drum and circumferentially are of an extent equaling the distance between the flanges of any pair of the longitudinal supporting members. The edges or edge portions of 95 said plates for engagement with said longitudinal members are bent to conform to the angle the supporting flange portion thereof presents with respect to a straight line extending from flange to flange of two of said 100 longitudinal members.

In addition, the screen plates are so mounted with respect to the longitudinal supporting members that the bent edges, or what may be termed the flanges of the successive plates, overlap each other circumferentially of the drum and are secured in place by bolts or rivets passing through two thicknesses of lapped plates and through the flanges of the longitudinal supporting 110

members of the frame; thereby providing a better anchorage for the plates than is possible with the former construction.

In the drawings, 1 represents one of the trunnions of a breaker or crusher structure of the Bradford type, to which a spider comprising a hub 3, radiating spokes 4, and a circular head structure 5, is connected; a similar arrangement being provided at the opposite end of the screen drum. The trunnions may be supported in suitable bearings 6, and these bearings may be hung from beams or girders 7, (one of which is shown), supported in any suitable manner.

Extending longitudinally between the head members 5, which may be in the form of truncated cones, are longitudinal supporting members 10, to which the screen plates 11, are secured, and the ends of these supporting members 10 may be secured to socket plates 12, suitably secured to said head structures 5, or said socket plates may be formed integral therewith. The longitudinal supporting members 10 may be of I-shape or other suitable cross section with the web set radially with respect to the axis of rotation, and it is to the inwardly disposed flanges 10^a of said longitudinal supporting members that the screen plates 11 are secured. The surface of these flanges is normal to the axis of rotation, or at right angles to planes passing through the axis of rotation, and in such relation each adjacent longitudinal member has a surface disposed at an oblique angle with respect to the others, and so on throughout the cylindrical portion of the screen structure.

The screen plates, indicated at 11, may be of any convenient size, usually about 30" square, and provided with perforations 11^a, whose size is dependent upon the work the screen is to accomplish. These plates are flat throughout their screening extent with slightly turned edge portions or flanges 11^b, whose angle with respect to the flat surface of the major portion of the screen plate accords with the angle of the flanges of the supporting members to which said plates are secured.

These screen plates are so mounted and secured to the longitudinal members 10 that each succeeding plate overlies or underlies the preceding one to the extent of the flanges of the supporting members to which they are secured. The flanges 11^b of each plate are provided with two rows or sets of holes 13 for the passage of securing means, which may be in the form of rivets, or headed bolts 14, secured by nuts 14^a and lock nuts 14^b; spring washers 14^c being preferably interposed between the nuts 14^a and the flanges of the supporting members, as clearly shown in Fig. 3. As these securing bolts pass through two plates and the flanges of the supporting members 10, it can be readily

seen that a very rigid construction is provided.

I have shown in Figs. 1, 2 and 3, flat plates 11, with bent edge portions forming flanges 11^b; the flange of one plate overlying the preceding or succeeding plate, as the case may be, when such plates are assembled to form the screen drum, and such overlying portions being disposed above the plane of the underlying plate. While this arrangement may be preferred in some instances, I have illustrated in Figs. 4 and 5 modified forms of screen plates having one edge joggled, as indicated at *x* and *x'*, respectively, such edge portion or flange being offset or recessed to such an extent that the plates when assembled will provide a drum having a substantially smooth inner surface.

In Fig. 4, I have illustrated a plate 111, with one edge *x*, offset or recessed with respect to the plane of the major portion of its surface and receiving the edge flange 11^b of the succeeding plate. In Fig. 5, substantially the same arrangement is shown except that the plates 111^a, which have one edge *x'* offset or recessed, are curved on the arc of a circle struck from the axis of rotation. In each instance the plates will be held to the longitudinal supporting members by two sets of retaining means; separate bolts 14, with nuts 14^a and 14^b, being shown in connection with the arrangement illustrated in Fig. 5, while in Fig. 4 I have shown a U-bolt 24, with its separate stems carrying the nuts 14^a and 14^b.

My improved construction involving the new type of plate and the manner of mounting and securing the same to the supporting members presents a number of important features which may be summed up as follows:

The ends of the screen plates are held in place by two sets of securing members and the plates act as a continuous beam, circumferentially of the drum. Such arrangement prevents bending of the plates as well as any leverage action on the securing bolts and eliminates any tension on the bolts which would tend to loosen them. As the bolts are under double shear, instead of single shear and tension, more than twice the strength is added to each bolt. While no more bolts are required with my arrangement over the prior construction, each screen plate is secured in place by twice the number of bolts heretofore employed in securing the screen plates in breaking or crushing structure of this type.

This condition, together with the change in stress on the bolts materially reduces the strain on each bolt. Any shearing action on the supporting members caused by the bolts is toward the centre of the same instead of toward the outer edges, and it is impossible for the bolts to tear any holes through the

- flanges of said supporting members. As the overlapping of the plates makes a practically continuous beam around the breaker drum, very little anchorage to the supporting members is actually required; in other words, the flat screen plates could be bolted together independently of the longitudinal supporting members and still provide an efficient screen structure.
- 16 I claim:
1. The combination, in a coal breaker, of a screening drum comprising a series of substantially flat screen plates having edge portions in flat planes differing from each other and from the plane of the main body of the plate; said edge portions being arranged in overlapping position, and means for securing the overlapping portions of said plates together.
  2. The combination, in a coal breaker, of a series of substantially flat screen plates disposed circumferentially and forming a screening drum, said plates having edge portions in flat planes differing from each other and from the plane of the main body of the plate with said edge portions in overlapping position, and means for securing said plates together at their overlapping portions.
  3. The combination, in a coal breaker, of a screening drum comprising longitudinal supporting members, and substantially flat screen plates having overlapping flanged edges secured to said longitudinal supporting members.
  4. The combination, in a coal breaker, of a screening drum comprising longitudinal supporting members, and a series of screen plates secured to said longitudinal supporting members; said screen plates being substantially flat and having edge flanges over-
- lapping each other circumferentially of the drum with the securing means passing through said overlapping portions.
5. The combination, in a coal breaker, of a screening drum comprising longitudinal supporting members, end supports for the same, and substantially flat screen plates having overlapping edge flanges secured to said longitudinal supporting members circumferentially of said drum.
6. The combination, in a coal breaker, of a screening drum comprising a series of longitudinal supporting members, and a series of flat screen plates having edge flanges in engagement with the longitudinal supporting members; said flanges having a width substantially equal to the engaging surface of the longitudinal supporting members and overlapping each other at the point of engagement, with securing means passing through said overlapping plates and the flanges of said supporting members.
7. The combination, in a coal breaker, of a screening drum comprising a series of longitudinal supporting members, end supports for the same, a series of flat screen plates having edge flanges in circumferential engagement with the longitudinal supporting members; said flanges having a width substantially equal to the engaging surface of the longitudinal supporting members and overlapping each other at the point of engagement therewith, and a plurality of securing members passing through said overlapping plates and the flanges of said supporting members.

In witness whereof I have signed this specification.

JOHN H. DOERRES.
